United States Patent Office.

JOHN H. WHITE, OF LIMA, PERU, AND WILLIAM S. HENSON, OF NEWARK, NEW JERSEY.

Letters Patent No. 86,264, dated January 26, 1869.

IMPROVEMENT IN CENTRIFUGAL-SCREW PUMPS.

The Schedule referred to in these Letters Patent and making part of the same.

To all whom it may concern:

Be it known that we, JOHN H. WHITE, of Lima, in Peru, South America, and WILLIAM S. HENSON, of Newark, in the county of Essex, and State of New Jersey, have invented a new and improved Centrifugal Screw-Pump; and we do hereby declare that the following is a full, clear, and exact description thereof, which will enable those skilled in the art to make and use the same, reference being had to the accompanying drawings, forming part of this specification.

This invention relates to a new and improved construction for pumps for raising water and other liquids; and

It consists in revolving a conical screw in a properly-constructed shell, and in the arrangement of the supply-valves in combination therewith, whereby the water is raised by the combined force of the revolving screw and centrifugal motion, as will be hereinafter more fully described.

Figure 1 is a central sectional elevation of the pump, showing the parts of which it is composed, and the method of its operation.

Figure 2 is a detailed view of the yoke by which the shaft of the pump is supported at its upper end.

Figure 3 is a detail, showing the conical screw, the view being from the bottom.

Figure 4 is a sectional detailed view of the upper part of the shell, showing the delivery-tube.

Figure 5 is a horizontal section through the line $z z$ of fig. 1, showing the arrangement of the supply-valves.

Similar letters of reference indicate corresponding parts.

A represents the shell or casing of the pump, which is stationary.

B B' is the revolving-screw cone. This is a double cone, the screw-thread being cut only upon the lower portion, as seen in the drawing.

D is the shaft by which the double cone is revolved.

C is the valve-section.

The shell is made in sections, the lower one, C, being the valve or supply-section by which the pump is fastened down.

This is a submerged pump, the design being to work it under water, as at the bottom of a cistern, well, or reservoir.

The shaft D, to which the double cone B is attached,

is stepped, into a central portion of the shell, as seen at e.

It will be seen that the supply-valves f are arranged so as to give the water a circular motion, and that the cone is revolved in an opposite direction, so that the threads of the screw dip the water from the opposing current, and elevate it in the channels between the threads and the shell, as indicated by the arrows, the water-passages around the cone being of equal area.

The current of water, in being thus elevated, is given a rapid whirling motion by the centrifugal force imparted; but this motion is counteracted by the ribs g, on the inside of the shell, so that the water is discharged in a smooth and solid stream from the pipe H.

The upper part of the shaft D is supported by the yoke J, from the bottom of which the shaft passes down into the shell, through a stuffing-box, as seen at I.

At the top of the yoke, the shaft is suspended in a self-oiling cup, K, by the collar L, which is fastened to the shaft by keys, as seen at m, fig. 1, and by the nuts n, above.

By unscrewing the bolts at o, the sections of the double-cone shell are separated, and the cone can be readily removed.

P is the pulley by which the shaft and cone are revolved.

Bevel-wheels and crank may be used instead of the pulley, if desired.

The quantity of water raised by the pump will, of course, depend upon the velocity with which it is driven.

We claim as new, and desire to secure by Letters Patent—

1. The double cone B B', in combination with the shell A, arranged and operating substantially as described, for the purposes set forth.

2. In combination with the screw-section B', the arrangement of the supply-valves in the valve-section C, substantially as and for the purposes set forth.

The above specification of our invention signed by us, this 10th day of June, 1869.

JOHN H. WHITE.
WM. S. HENSON.
